UNITED STATES PATENT OFFICE.

ELMER W. COKELY, OF COALINGA, CALIFORNIA.

FRICITION-HOIST GEAR.

No. 903,057.

Specification of Letters Patent.

Patented Nov. 3, 1908.

Application filed October 21, 1907. Serial No. 398,454.

To all whom it may concern:

Be it known that I, ELMER W. COKELY, a citizen of the United States, residing at Coalinga, in the county of Fresno and State of California, have invented a new and useful Friction-Hoist Gear, of which the following is a specification in such full and clear terms as will enable those skilled in the art to construct and use the same.

10 This invention relates to reels used for the purpose of taking the sand and broken rock out of the bottom of an oil, gas, or water well after the drilling has proceeded to such a point as to make the cleaning of the well necessary.

An object of the invention is to produce a reel that will be provided with supports that will move sufficiently to throw the weight of the reel far enough off the center of support 20 to cause it to hug the winding drum closely and to cause the brake to hold the drum equally well.

A further object of the invention is to make a hoist which will have its levers well 25 out of the way of the person using the hoist.

A further object of the invention is to provide a means for holding the friction drum shaft in such a manner as to allow its shaft considerable play since when it is moved forward or back each side may not move precisely the same amount.

A further object of the invention is to provide means whereby the reel will automatically lock itself when thrown against the 35 friction wheel or against the back brake, as the case may be.

In the drawings, in which the same numerals are applied to like parts throughout, Figure 1 is a front elevation of a part of an 40 oil rig showing this friction hoist, Fig. 2 is a side elevation of the same part of an oil rig showing the friction hoist, Fig. 3 is a view of one means for allowing the drum to have a slight play, Fig. 4 is a plan of the same device 45 shown in Fig. 3, Fig. 5 is an edge elevation of the swinging link which supports the drum, Fig. 6 is a front view of said link, Fig. 7 is a view of the platform at the driller's station, Fig. 8 is a side elevation of one half of the 50 preferred form of the drum box and its support, Fig. 9 is a plan of the drum box support, and Fig. 10 is a side elevation of one form of the lower portion of the drum box and its support.

55 The numeral 1 represents the bottom sill of the oil rig frame, and 2 is the side sill of the

same only such parts of the rig being shown as are material to the present invention. The frame is provided with the perpendicular brake post 3 and the band wheel post 4 60 said band wheel post being set in a mortise in the sill 2 and held in place therein by the block 5. The band wheel 6 is supported by the post 4 on the top thereof said wheel being of large diameter and driven from any suitable source of power.

Carried by the sills of the machine are four supporting arches 7 which are bolted to the sills. These arches are provided on their upper edges with a series of curved depressions 70 8, shown in Fig. 2, and which are placed at about the center of the points of contact of the friction drum 9 with the band wheel 6 and the brake post 3. The arches are also provided with a cover plate 10 which is 75 bolted to them.

The sand reel drum 11 is carried by the shaft 12 which also carries the friction drum 9. This shaft is supported in a pair of boxes 13 which each have a depending ear 14, said 80 ear passing between ears of the supporting blocks 15, bolts passing through the ears and the supporting blocks 15 to hold the boxes in their places. This supporting block has holes through it at right angles to each other 85 as shown in Figs. 8 and 9, the purpose of said holes being to allow one bolt to pass through to secure the box in its place in such a manner that it may rock. The hole shown in Fig. 9 is for the purpose of allowing the bolt 90 16 to pass through to secure the block to the swinging link and to allow the block to turn in a horizontal plane.

The supporting link 17 is carried by the hanger 18 which in turn is supported by the 95 arches 7, the pivots 19 being placed in the curved depressions 8 of the arches 7. Attached to the supporting link 17 is the rod 20 which runs up high enough to give the proper leverage, and which is connected to the rod 100 21, said rod 21 being supported by the bracket 22 and rod 23, the bracket 22 being bolted to the post 4, and the rod 23 extending down far enough to be below the top of the sill 2 to a long rod 24 which runs to the 105 platform of the person operating the rig. This rod 24 is connected to the lever 25 which is operated by the hand lever 26 on the platform 27 by the engineer's side.

Now it will be clear that it is not necessary 110 to have the left hand end of the shaft supported by the same kind of a link as the end

next the friction drum it only being necessary to have it loose enough to allow the necessary play at the friction drum end to allow the drum to make the requisite movements 5 to touch the brake post and the band wheel, which in practice are but a short distance apart more than the actual length of the chord of the friction drum 9.

It will be observed that the total weight of 10 the friction drum with its coils of rope or cable is in the neighborhood of from 3000 to 4000 pounds so that when it is pulled to the position shown in Fig. 2 it kicks the hanger back out of the perpendicular indicated by 15 the dotted line and this makes the drum hug the band wheel that much closer since to move it back to contact with the brake post it must be pushed from above and pass over the center of support of the hanger 18 when 20 the hanger will at once kick back in the opposite direction and make it lock itself in that position.

The drum 9 bears against the face of the band wheel 6, which is lagged with any suitable materials that may be at hand and the post 3 may or may not be lagged at the place of contact with the friction drum, but in any event the lagging or the face of the post wears away as the drilling of the well proceeds and it frequently becomes necessary to change the position of the hanger 18 to make it swing the friction drum with its load of rope properly against the band wheel and the brake post 3.

35 From the above description it is thought that the operation of the hoist will be clear, it being understood that the band wheel is used when it is desired to hoist the rope with its load of tools and mud and the brake when 40 it is desired to stop the drum, the time being so short between the movement of the drum from the brake to the post, or vice versa, as to prevent the undesired unwinding of the rope on the drum 11.

45 It will be clear that the single ear 14 of the bearing boxes 13 may be made into two as shown in Fig. 10, if desired, in which case the part secured to the swinging link 17 will be simply a block 15' with two holes therein and 50 the lower part of the bearing box will have two ears instead of one, the effect being a reversal of the construction shown in the other figures.

What I claim as my invention and desire 55 to secure by Letters Patent of the United States is as follows:

1. In a friction hoist, the combination with a friction drum of means to move the drum forward and back, a friction wheel, a 60 brake post on the opposite side of the drum from the friction wheel, a swinging hanger and a movable link supporting the drum and carried by the swinging hanger.

2. In a friction hoist, the combination 65 with a friction drum of means to move the

drum forward and back, a friction wheel in front of the drum, a brake post in the rear thereof and on the opposite side of the drum from the friction wheel, a lever to move the drum, a movable hanger for the end of the 70 friction drum adjacent the lever which moves it back and forth, a movable link supporting the drum and carried by the hanger, and connections co-operating with said lever whereby said drum may be moved from a 75 distance.

3. In a friction hoist, the combination of a friction drum, a friction wheel adjacent the drum, a brake post on the opposite side of the drum from the friction wheel, means to 80 move the drum from a distance, a pivoted hanger, and a link carried by the hanger for supporting the friction drum whereby it may be moved into and out of contact with the brake post and friction wheel.

4. The combination of a friction drum, a friction wheel adjacent the drum, a brake post adjacent the drum and on the opposite side thereof from the friction wheel, a swinging hanger for the drum and comprising a 90 connected pair of links having oppositely extending pivots at their upper ends and a connecting pin at their lower ends, and means to move the drum toward and away from the brake post and the friction wheel.

5. The combination of a friction drum, a friction wheel adjacent the drum, a brake post adjacent the drum and on the opposite side thereof from the friction wheel, a swinging hanger supporting the drum and comprising a pair of links having oppositely extending pivots at their tops and a connecting pin at their bottoms, an arched support for the hanger and having a series of depressions for the hanger pivots whereby the same may 100 be adjusted with respect to the brake post and the face of the friction wheel.

6. The combination of a friction drum, a friction wheel adjacent the drum, a brake post on the opposite side of the drum from the friction wheel, a swinging hanger supporting the friction drum, an arched support for the hanger and means to move the drum toward the friction wheel and the brake post 110 at will.

7. The combination of a friction drum having a shaft and bearing boxes, a friction wheel adjacent the drum, a brake post on the opposite side of the drum from the friction wheel, a swinging hanger for the drum, a 120 link connected to the hanger and to the bearing box of the drum, and means to move the drum toward and from the friction wheel and the brake post at will.

8. The combination of a friction drum 125 having a shaft and bearing boxes, a friction wheel adjacent the drum, a brake post adjacent the drum and on the opposite side of the drum from the friction wheel, a swinging hanger for the drum, means to move the 130

drum toward and from the brake post and friction wheel, and means to lock the drum against the friction wheel or the brake post at will.

- 5 9. The combination of a friction drum having a shaft and bearing boxes, a friction wheel adjacent the drum and adapted to drive the drum when the same is pushed into contact with the same, a brake post on the
10 opposite side of the drum from the wheel, a pivoted link suspending the drum and adapted to permit the drum to be swung into contact with the brake post or the friction wheel, an arched support for the link and having a

series of notches in which the supporting members of the link may be placed whereby the same is adjusted with respect to the post and drum, and means to move the drum toward and from the post and friction wheel at will.

20 In testimony whereof I have set my hand this fifth day of October A. D. 1907, in the presence of the two subscribed witnesses.
